UNITED STATES PATENT OFFICE.

EMIL E. STREED, OF ST. CHARLES, ILLINOIS.

LACING-STUD.

SPECIFICATION forming part of Letters Patent No. 769,329, dated September 6, 1904.

Application filed December 15, 1902. Serial No. 135,199. (No model.)

To all whom it may concern:

Be it known that I, EMILE E. STREED, a citizen of the United States of America, and a resident of St. Charles, in the county of Kane and State 5 of Illinois, have invented certain new and useful Improvements in Lacing-Studs, of which the following is a specification.

The present invention relates to that class of lacing-studs used on shoes, gloves, and other articles of personal wear, and has for its object to provide a simple and efficient construction and arrangement of parts whereby a strong and effective attachment of the stud may be had and with which the hook portion of the stud is shielded from an accidental and very annoying engagement with the clothes of the wearer, all as will hereinafter more fully appear, and be more particularly pointed out in the claims.

20 In the accompanying drawings, illustrative of the present invention, Figure 1 is a perspective view of a lacing-stud attached to a fragment of fabric and embodying the present invention. Fig. 2 is a top view of the same; 25 Fig. 3, a longitudinal section at line $\alpha\alpha$, Fig. 2; Fig. 4, a plan view of the blank from which the present lacing-stud is formed.

Similar numerals of reference indicate like parts in the several views.

30 Referring to the drawings, 1 represents the base portion of the lacing-stud having the usual integrally-formed tubular attaching-shank 2 and lace-engaging hook 3, the parts being of any usual and ordinary form.

35 In the present improvement the lacing-stud, as above described, is formed as follows: 4 is an extension or tongue formed at one end of the base and bent up, as shown in the drawings, to form an angular guard-tooth 5 in line 40 with the mouth or entrance-opening of the lace-engaging hook 3 and a short distance back of the same to permit of an engagement of the lace with said hook. The tooth 5 in the preferred construction, as shown in the

drawings, has a substantially vertical side facing the hook and a sloping or inclined side to the rear thereof, as shown, and as so formed is adapted to prevent in a very perfect manner any accidental engagement of the hook with the clothes of the wearer, &c. 45 50

6 is a clenching-spur at the rear or free end of the tongue or extension 4 for securing such end of the lacing-stud to the shoe or other article, with the angular guard-tooth 5 in proper relation to the open end of the lace-engaging hook 3, and at the same time afford additional means of attachment for the lacing-stud to the shoe or other article. 55

Having thus fully described my said invention, what I claim as new, and desire to secure 60 by Letters Patent, is—

1. As an improved article of manufacture, an integrally-formed lacing-stud formed of sheet metal and comprising an attaching-base, a lace-engaging hook, and a central angular guard-tooth formed by an indentation in the base and arranged to the rear of the open end of said hook, the forward portion of said angular tooth being perpendicular to said base and directly opposite the open end of the lace-engaging hook. 70 65

2. As an improved article of manufacture, an integrally-formed lacing-stud formed of sheet metal and comprising an attaching-base, a tubular attaching-shank, a lace-engaging hook, and a central angular guard-tooth formed by an indentation in the base and arranged to the rear of the open end of said hook, the forward portion of said angular tooth being perpendicular to said base and directly opposite the open end of the lace-engaging hook. 75
80

Signed at Chicago, Illinois, this 8th day of December, 1902.

EMIL E. STREED.
